UNITED STATES PATENT OFFICE

2,656,636

FIRING MECHANISM FOR FIREARMS

Samuel G. Green, Gray, Ga.

Application October 25, 1950, Serial No. 192,100

1 Claim. (Cl. 42—69)

(Granted under Title 35, U. S. Code (1952),
sec. 266)

1

The invention described in the specification and claims may be manufactured and used by or for the Government for governmental purposes without the payment of any royalty thereon.

This invention relates to automatic guns and more specifically to improvements in firing pin mechanisms for machine guns having a high firing rate.

An object of the invention is a firing pin mechanism for the elimination of primer base blowing.

Another object of the invention is the reduction of mass of the firing pin assembly which travels rearwardly at high velocity recoil to contact the sear.

Another object of the invention is the elimination of alignment requirements which in the conventional firing pin requires three bearings to give the pin necessary physical support.

Another object of the invention is a firing pin having its primer contacting member made of alloy steel to withstand the erosion effect of the corrosive gases and the rear section made of carbon steel since it is not subjected to elevated temperatures or the erosive or corrosive effect of powder gases.

Another object of the invention is the combination of a recoil plate and front section firing pin assembly arranged so that the best conditions of guiding, sealing and functioning can be assured.

Another object of the invention is the elimination of the excessive recoil of the firing pin and firing pin extension experienced when the one piece firing pin is employed.

Another object of the invention is placing the rearward movement of the firing pin assembly under the mechanical control of the cocking lever, so as to assure correct timing of the firing mechanism.

The specific nature of the invention as well as other objects and advantages thereof will clearly appear from the following description and accompanying drawings in which:

Figure 1 is a vertical sectional view taken along the longitudinal axis of the bolt, showing the firing pin mechanism in position just prior to the bolt going into recoil;

Figure 2 is a sectional view taken along the longitudinal axis of the bolt showing the floating striker and firing pin of the invention;

Figure 3 is an end view of the striker and firing pin shown in Figure 2;

Figure 4 is a fragmentary vertical sectional view taken along the longitudinal axis of the bolt showing a modification of the arrangement in Figure 1.

2

The current type of firing pin, which is a one piece pin, for an automatic gun operating at a rate of approximately 1200 rounds per minute is subjected to severe impact due to the high spring load required to drive the firing pin in order to fire the cartridge in the short interval after the gun is nearing the in-battery position. In addition to the foregoing, the use of high pressures in ammunition to obtain higher required projectile velocities has resulted in a greater setback load on the primer base of the cartridge and firing pin so as to induce pierced and blown primers. The blowing of the primer imparts an abnormal force to the one piece firing pin causing it to be driven violently and hammer the firing pin extension against the sear member. The improved firing pin mechanism of this invention is provided with a floating striker member supporting a firing pin which has a setback but slightly greater than the protrusion of the firing pin beyond the face of the recoil plate. A plunger extension member is provided with a relatively light spring for actuating a plunger member intermediate the striker and extension. Due to the limited setback of the firing pin the primer base is supported during the firing period which prevents the primer base from setting back so as to be pierced.

In Figure 1 there is shown a preferred embodiment of the invention wherein reference numeral 1 indicates a bolt having bore 2 therein housing a firing pin mechanism comprising striker 3, plunger 4, plunger bearing 5 threadably secured within bore 2, plunger extension member 6 and plunger driving spring 7. Reference numeral 8 indicates the usual cocking lever, which has one end 9 for engagement with the top plate bracket 10 and its opposite end 11 for engagement with the plunger extension member 6, and 12 indicates the sear. Fixed in the front end of bore 2 is a recoil plate 13 provided with a bore 13a having a reduced portion 13b forming a shoulder 13c intermediate the ends of the bore 13a. The firing pin 14 is slidably received in reduced portion 13b for engagement with primer base 20. For a short distance behind the recoil plate the bore 2 is reduced as indicated by reference numeral 15 providing bearing surface for the slotted body 16 of the striker member 3. The slots being indicated at 17. The rearward motion of the striker 3 is arrested by the plunger bearing 5 which has its forward end spaced a predetermined distance from the reduced portion 15 of the bore 2. The head 18 in counterrecoil movement contacts the cup 19a to limit the counterrecoil movement of the body

16 and pin 14. A port 15a intersects the reduced portion 15 of the bore 2 intermediate its ends to permit gases to be discharged from the slots 17 to the exterior of bolt 1. The body 16 of striker 3 projects rearwardly in the bore 2 beyond the reduced portion 15 and is provided with a head 18 in operable relation to the plunger 4. A spring 19 housed in a cup member 19a is placed about the body 16 and positioned between the head 18 and reduced portion 15 resiliently spaces the firing pin 14 from the primer base 20 of the cartridge 21. The plunger 4 is provided with a flange 22 which abuts one end of the plunger bearing 5 and limits the forward travel of the plunger. Adjacent to the flange 22, the plunger 4 is affixed to one end of the plunger extension 6 as by means of pin 23. The sear stop assembly 24 has a pin 25 extending through the slot 26 in the plunger extension 6. The spring 7 is positioned in the slot 26 between pin 23 and pin 25 of the sear stop assembly.

Figure 4 illustrates a modified form of the invention wherein there is a bolt 30 having a bore 31 reduced as at 31a to accommodate a plunger 32 which has its forward end extended into a bore 33 of the recoil plate 34. In the bore 33 of the recoil plate there is positioned a striker member 35 having affixed to its forward end a firing pin 36 and a flange 37 at its opposite end for engagement with the plunger 32. A spring 38 resiliently spaces the striker member from the cartridge. The firing pin is longitudinally supported by the walls of the reduced section 33a of the bore 33.

In operation the sear releases the plunger extension and the spring therein drives the extension and plunger which drive the striker member to cause the firing pin to indent the base of the primer and fire the primer, the base of which is supported not only by the recoil plate, but in part by the firing pin which when in recoil position is substantially flush with the exposed surface of the recoil plate.

In the usual type of firing pin, the pin in recoil travels the entire distance required for engagement of the extension with the sear and leaves the center of the base of the primer unsupported to be blown into the bore in which the pin travels and results in excessive recoil of the pin. This excessive recoil causes a heavy impact load on the sear and the firing pin extension which rebounds and obtains false engagement with the sear. The extension releases before the firing point of the bolt is reached to cause a riding down of the conventional firing pin and extension on the cocking lever which is purposely blocking the firing pin assembly before the release position is reached and results in a light blow and failure to fire the cartridge. The firing pin mechanism of this invention eliminates the foregoing since the firing pin and striker are

arrested in the recoil travel, leaving the plunger and extension under the mechanical control of the cocking lever to assure correct timing of the firing mechanism.

I claim:

In an automatic firearm; a bolt reciprocable therein between recoil and battery positions, there being an elongated horizontal stepped bore formed in said bolt and comprising a short forward enlarged portion, an elongated medial portion of reduced diameter, and a rear enlarged portion; a firing pin and plunger mechanism reciprocable in said horizontal bore and comprising, a floating striker slidably in said forward enlarged bore portion, said striker including a main body portion providing a sliding fit with the wall of said forward enlarged portion, and a forward reduced portion forming a firing pin, means in said forward enlarged bore limiting the forward movement of said striker in counter-recoil to provide a predetermined protrusion of said firing pin beyond the forward wall of said bolt when said gun is fired; resilient means cooperating with said forward movement limiting means to normally urge said striker into retracted position with the forward end of said firing pin flush with the forward wall of said bolt, said striker being limited in rearward movement to an extent slightly in excess of said predetermined protrusion by the shoulder formed by said forward enlarged bore portion and said medial reduced bore portion; an elongated tubular plunger reciprocable in said medial reduced portion for positive engagement with said striker, 35 a flanged enlargement on the rear end of said plunger, said enlargement slidably engaging said enlarged rear bore portion, said enlargement also adapted to abut the shoulder between said enlarged rear bore portion and said medial bore portion when said gun is fired to limit the forward travel of said plunger, a hollow sleeve in said enlarged rear bore portion integral with said enlargement, a helical spring in said hollow sleeve having its forward end engaging said enlargement and its rear end abutting a stop member integral with said bolt, said helical spring being compressed by the rearward movement of said bolt, whereby on release of said bolt said spring drives said plunger forward to propel said firing pin into contact with the primer of a propellant cartridge.
